UNITED STATES PATENT OFFICE

LEWIS I. KAHN, OF BROOKLYN, NEW YORK

TABLE PAD

Application filed August 7, 1931. Serial No. 555,827.

This invention relates to table pads and has for an object to provide an improved construction wherein the pad is formed with a plurality of sections and each section folded in order that the pad may be readily stored when not in use.

Another object of the invention is to provide a table pad formed of paper, asbestos or other material with suitable coverings, the body of the pad being divided preferably centrally with offset portions overlapping and coacting with disengageable fastening means, thus permitting the pad to be readily handled and yet held together when in use.

An additional object, more specifically, is to provide a table pad divided in two or more sections with the adjacent parts of the sections overlapping and with disengageable fastening members arranged so that one fastening member is stationary and the other slideable, thus permitting a slight expansion or contraction of the respective parts.

In the accompanying drawing—

Figure 1 is a top plan view of a complete pad disclosing an embodiment of the invention, the portion of the pad being broken away for illustrating one of the fastener structures.

Figure 2 is an enlarged sectional view through Figure 1 on line 2—2.

Figure 3 is an enlarged, fragmentary sectional view through Figure 1 on line 3—3.

Figure 4 is a fragmentary sectional view through one edge of one of the sections shown in Figure 1.

Figure 5 is a perspective view showing one of the sections illustrated in Figure 1 in a folded position.

Figure 6 is a perspective view of a modified fastener plate.

Figure 7 is a sectional view through a modified form of stud and fastener plate.

Figure 8 is a sectional view through a modified form of socket and fastener plate.

Figure 9 is an inverted perspective view of another form of fastening plate.

Referring to the accompanying drawing by numerals, 1 indicates a body divided into sections 2 and 3, said sections being connected together by disengageable fastening mem-

bers 4 and 5. It will be noted that each section is divided along the respective lines 6 and 7 so that the parts may be folded as shown in Figure 5. In forming the sections 2 and 3, the adjacent or abutting edges are formed as shown in Figure 4. From this figure, it will be seen that the body 8 of the pad is cut away to form a notch 9. The covering felt 10 extends over the extension 11 and is tucked in between certain layers of the body 8 as indicated at 12. The covering cloth 13 passes over the edge 14 and is tucked in at 15. It will be understood that the coverings 10 and 13 are cemented or held in place by any desired adhesive. The notch 9 in each of the sections is the same size so that the extension 11 of one section may overlap extension 11 of the next section whereby a smooth upper surface will be presented as shown in Figure 1.

The disengageable fastener 4 is simply a stud and socket secured in any desired way to the respective sections. This fastening member is engaged with the fastener member 5. The fastener member 5 is a special structure and includes a sliding stud 16 slidably mounted on a plate 17 which may be cemented or otherwise secured to the body 8. As illustrated in the drawing, the stud 16 is cemented, stapled, or otherwise connected with section 2 while the opposite section carries a socket similar to the socket 18 shown in Figure 8. This socket may be held in place by a plate similar to plate 17 or by a metallic plate as shown in Figure 8. The plate 19 carries prongs 20 and 21 which extend into the body 8 and may be clinched if desired. The principal feature in this form of the invention is the fact that one of the fastener elements is stationary and the other slideable. This compensates for a slight inequality in length by reason of the expansion or contraction or other causes.

Instead of using the plate 17 as shown in Figure 3, a metal plate 22 could be used, said metal plate being provided with prongs 23 and 24 adapted to be forced into the body 8 and clinched if desired.

In a similar way, a further modified form

of plate 25 could be used, the same having prongs 26 and 27 similar to the other prongs in Figures 7 and 8. In the plate 25, a slot 28 is provided which is large enough to receive a stud carried by one of the sections, while the plate 25 would be secured to the other sections. This would allow the stud to slide back and forth, but would hold the respective sections together and in line.

10 In forming the pad, the body 8 may be made of any number desired of layers of pasteboard, cardboard, asbestos or other material, or preferably material which is heat-insulating and also comparatively cheap. A 15 certain number of these layers are secured together by suitable staples 29 and then the top and bottom layers 30 and 31 mounted on the previous layers and cemented thereto. After this has been done, the covers 10 and 20 13 are placed in position. Wherever possible the edges are forced between certain of the layers of the body 8 as indicated at 32. Before the covers 10 and 13 are placed in position, strips 33 and 34 are cemented in place, 25 said strips being of any desired material, but preferably is a strong piece of cloth whereby they may act as hinges so that when the parts are folded as shown in Figure 5, these members will permit the parts for each section to 30 fold. There are three folding parts in each section as shown in the drawing, but it will be evident that a large number or even a less number may be made without departing from the spirit of the invention. The pad 35 has been shown as being square except for the corners, but it is evident that the pad could be made round or some other shape, and still embody the features above set forth.

In Figure 9, another form of fastening 40 plate is shown wherein the stud 16' slides in a similar manner to the way it slides in Figure 3, but is applied to a metal plate 33 having depending flanges 34 and 35 whereby it is spaced from the bottom of a recess so that the stud may freely slide while at the same time spurs may be bent over to clamp the plate tightly in position.

I claim:

1. A pad comprising a body formed with a 45 plurality of sections, each section being divided into a plurality of parts, strips of cloth secured to adjacent parts for hingedly connecting said parts together, a continuous covering member positioned to cover all of said 50 parts and said strips of cloth, each of said sections along their abutting edges being notched and overlapped, and disengageable means for fastening said sections together one of said means being fixed and the other 55 slid able.

2. A table pad comprising a body with two 60 sections provided with reduced extensions, said extensions overlapping, a snap fastener arranged adjacent one end of said overlapping portions for disengageably securing the

sections together, a snap fastener arranged adjacent the opposite end of said overlapped portions, said last mentioned snap fastener having one of the inter-engaging elements 70 slidably secured to a section.

3. A table pad comprising a body divided into two sections, a pair of disengageable fastening means for fastening said sections together, said fastening means consisting of snap fasteners, a retaining plate for each part 75 of the fastener, said plates being secured respectively to the different sections, one of said plates being provided with a slot so that the part of the fastener connected therewith may slide, said slot extending substantially 80 parallel to the edge of the section to which it is secured.
